UNITED STATES PATENT OFFICE.

JAMES W. BROOKS, OF CHICAGO, ILLINOIS.

DESICCATOR.

1,266,915.

Specification of Letters Patent. Patented May 21, 1918.

Application filed June 25, 1917. Serial No. 176,777.

To all whom it may concern:

Be it known that I, JAMES W. BROOKS, a citizen of the United States, and a resident of the city of Chicago, county of Cook, and 5 State of Illinois, have invented certain new and useful Improvements in Desiccators, of which the following is a specification.

My invention relates to the provision of suitable facilities for conveniently and economically desiccating comestibles having a considerable amount of water or moisture therein, such as vegetables, fruits and the like, which will effect the removal of the water or moisture in an expeditious manner 10 without otherwise changing the constitution of the article treated, so that the esculent properties and flavor thereof may be retained unimpaired and the articles so treated may be kept indefinitely.

One of the objects of my invention is to provide a suitable and convenient receptacle for the articles during treatment and to cause a proper circulation therethrough of the drying medium. In order to effectuate 20 this object, I have provided means for controlling the circulation of the drying medium so that the circulation can be regulated to secure the best results upon the particular article under treatment, and I 25 have also provided means for the admission of fresh quantities of the drying medium to each tray of articles under treatment, so that the last articles reached by the current or 30 the circulation of the drying medium will not be dependent upon the action of the medium already charged with the moisture removed or absorbed from the articles on the preceding trays. Further objects of my 35 invention include the provision of a desiccator that is comparatively simple in construction, economical to manufacture, dependable in its operation, and which is as well adapted for domestic or household use 40 as for operations on a larger scale.

So far as I am now aware, the desiccation 45 of fruits, which are the only articles now generally preserved in that manner, is accomplished by exposing the cut fruits to the action of sun and wind, or to a considerable 50 degree of heat. The operation of drying in the sun is long and tedious and exposes the articles to contamination by flying dust, while the use of any considerable degree of 55 heat changes the constitutions of the articles and particularly affects the natural flavor thereof, so that they are rendered insipid.

and unpalatable. With my invention time is very much conserved, as fruits having any considerable amount of water or moisture, such as strawberries, apples, peaches and 60 pears, may be dried within six hours, and vegetables, such as corn, potatoes, green beans and other succulents, may be dried in a like length of time. Also with my invention the articles during treatment are 65 protected from contamination.

I prefer to accomplish the divers objects of my invention by substantially the means and in the manner hereinafter fully described and as more particularly pointed out 70 in the claims, reference being had to the accompanying drawings that form a part of this specification, in which,—

Figure 1 is a perspective view of my improved desiccator.

Fig. 2 is a longitudinal vertical section through the central portion of my apparatus.

Fig. 3 is a transverse vertical section taken on line 3—3, of Fig. 2, and looking in the 80 direction indicated by the arrows.

Fig. 4 is a detail view of the baffle or similar heat distributing element employed in conjunction with my apparatus.

In the drawings I have employed similar 85 reference characters to designate the same or similar parts throughout the divers figures. Referring to the drawings, it will be observed my apparatus preferably comprises a rectangular shaped compartment that is 90 preferably constructed of wood, metal or any suitable material that may be found desirable, and consists of vertical longitudinal side walls 10, 10 and a rear wall 11 that connects the vertical rear edges thereof. The 95 front wall may consist of a rectangular shaped open frame 12, provided with a panel 13, of glass or other suitable transparent material, said frame being secured to the front edge of one of the side walls by means 100 of hinges 14, or in any other suitable manner.

Within the compartment thus formed I prefer to provide a plurality of racks or 105 trays 15, disposed one above the other, with their longitudinal side edges resting upon suitable horizontal cleats or rests 16 that are disposed opposite each other, each pair of cleats being in different horizontal planes. The trays just referred to are of woven wire 110 or of a suitable mesh to prevent articles placed thereon from slipping through the inter-

stices thereof. The woven wire has its edges turned over a suitable metal or wooden frame 17 of a size to conveniently fit within the compartment and be easily removed therefrom. A screen 18, of suitable construction, preferably similar to the trays 15 hereinbefore described, is placed upon the top of the compartment, either resting upon the upper edges of the walls or upon a suitable rabbet 19 made in the upper edges of the walls, substantially as shown in Figs. 3 and 4 of the drawings.

In order to secure a circulation of air which will absorb and abstract the moisture from the material to be dried, a source of heat may be employed which will cause the air to rise and thus produce a circulation. The small amount of heat necessary to produce a requisite circulation will increase the absorbing capabilities of the air without deleteriously affecting the articles under treatment.

The compartment above described, when employed for domestic uses, is adapted to be placed upon a gas stove or similar device, above a burner so that the heated air arising from the flame will enter the compartment and act upon the articles on the trays. In order to prevent a too rapid rise of the air and also to avoid the flame having a harmful action upon the lower tray and the articles thereon, I have provided a suitable baffle, illustrated in detail in Fig. 4 of the drawings, which comprises a flat, rectangular-shaped piece of metal 20, of sufficient dimensions to cover the flame of the heater, and mounted upon the same, but spaced therefrom a suitable distance, is a second or spreader-plate 21, of slightly greater dimensions than the baffle-plate 20, and is retained in spaced relation to said baffle plate by means of suitable spacers 22, that connect said plates.

In operation, the articles to be dried are placed upon the trays 15 and the latter inserted into the compartment upon their respective guides or cleats and the baffle placed above the burner so that the flame will not rise and injure the articles on the lowermost tray, and the front door 12 is then closed. The heated air arising from the flame will be distributed by the spreader-plate 21 and circulate through the interstices and between the articles upon the trays and pass out at the top of the compartment which is open. In order to regulate the amount of air passing through the compartment, I prefer to employ a damper which preferably comprises a sheet of woven fabric, such as linen or the like, that is laid loosely upon the top of the compartment above the screen 18, and is adapted to be drawn back a slight distance, at the ends or sides, to permit the more ready egress of the air after circulation through the compartment. I prefer to

provide means for admitting fresh quantities of air to the compartment, and to this end I bore a plurality of openings or small holes 24 in the side walls of the compartment, the said openings being disposed in horizontal rows, each row being located approximately midway between two trays. This adds fresh air which has had no opportunity to absorb any of the moisture, and provides a means of treating each tray with substantially the same character of drying medium, so that all of the articles on the trays will dry simultaneously and at a uniform speed. It will be understood that the creation of a current of the drying medium in the compartment will draw the fresh outside air through the openings or ports above described, thereby constituting a thermosiphonic circulation through the apparatus. It will also be understood that the drying medium may be previously dried before its circulation through the compartment, but a satisfactory operation of my apparatus for domestic purposes may be had with ordinary atmospheric air which has not been previously dried.

I have herein disclosed a typical desiccator constructed in accordance with the principles of my invention, the drawings being, in a sense, merely diagrammatic, as illustrating the principles involved. It will be obvious to others skilled in this art that modifications or refinements of the structure may be made without materially departing from the principles thereof; as, for example, the structure may be made of metal instead of wood, as illustrated, or may be made upon a larger and more elaborate scale for commercial use. All such changes or alterations are contemplated as included within the scope of my invention as expressed in the appended claims.

What I claim is:

1. A desiccator comprising a compartment, open at its bottom, means for creating a current of air therethrough, a textile cover for controlling the quantity of air passing through said compartment, reticulated trays, spaced means in said compartment for the reception and support of said trays, and opposite rows of ports disposed between the respective tray supports whereby fresh air is adapted to be drawn therethrough into said compartment above each tray by the current of air circulating therein.

2. A desiccator comprising a compartment open at its bottom, means at the bottom thereof for creating a current of air upwardly therethrough, a textile cover at the top of said compartment for controlling the current of air passing therethrough, reticulated trays, means for supporting said trays within said compartment, and opposite rows of ports disposed between said trays whereby fresh air is adapted to be

drawn through the same into said compartment above each tray by the current of air circulating therein.

3. A desiccator comprising a compartment open at its bottom, means at the bottom thereof for creating a current of air upwardly therethrough, a textile cover at the top of said compartment for controlling the current of air passing therethrough, reticulated trays, spaced means in said compartment for the reception and support of said trays, and several opposite rows of ports disposed intermediate said respective tray supports whereby fresh air is adapted to be drawn therethrough into said compartment above each tray by the current of air circulating therein.

4. A desiccator comprising a substantially rectangular shaped compartment open at its bottom, means therein for receiving articles to be treated, a source of heat, a reticulated cover disposed upon the top of said compartment, means for regulating the quantity of drying medium passing through said compartment, a baffle structure above said heat source, and means for supplying fresh air to said compartment intermediate the article-receiving means.

5. A desiccator comprising a substantially rectangular shaped compartment open at its

bottom, a plurality of removable trays disposed therein, a source of heat adjacent the bottom in said compartment, a screen covering the top of said compartment, means regulating the quantity of drying medium passing through said compartment, a baffle structure above said heat source, and means for supplying fresh air to said compartment intermediate said trays.

6. A desiccator comprising a substantially rectangular shaped compartment open at its bottom, a plurality of reticulated trays removably disposed therein, a source of heat adjacent the bottom of said compartment, a reticulated cover for the top of said compartment, a baffle structure above said heat source, means for supplying fresh air to said compartment intermediate the trays, and means for regulating the quantity of drying medium passing through said compartment consisting of a piece of fabric removably disposed upon said cover and capable of being moved about thereon.

Signed at Chicago, county of Cook and State of Illinois, this 6th day of June, 1917. 55

JAMES W. BROOKS.
